SNAP SWITCHES

1 Chester W. Johnson, Bridgewater, Mass.

Application October 21, 1952, Serial No. 315,929

4 Claims. (Cl. 200—67)

This invention relates to switches for controlling electric circuits, and particularly to wall switches of the so-called toggle type used in homes and offices for controlling lighting circuits.

The main object of the present invention is to provide a switch of this type which will be practically noiseless in operation, while retaining the essential features of quick make and break of the circuit, of avoiding the stopping of the parts in intermediate position between the off and on extremes of their movement, of intermittent or trembling contact in the on-position with resultant arcing constituting a fire hazard, and of reverse creep of the parts out of their intended on or off position. Other objects of the invention include the provision of a simple structure which can be easily and rapidly assembled out of inexpensive components of wide availability to make a switch having long life and freedom from failure in action.

The basic principle employed in the novel snap switch to attain noiseless action is the checking of the moving parts and ending their travel not by striking against stops, but by the wedging or jamming action and resultant friction of surfaces travelling with the moving parts against other stationary parts, herein by the binding action of shoes pivotally attached respectively to the thumb piece and to the spring carrier and sliding along guides. The divergent course of each pivot with respect to its associated guide or other interfering surface, disposed in non-parallel relation to the path of travel of the moving part and the pivot, causes the shoe to bind on the guide and arrest the motion of the pivot and thus of the thumb piece or spring carrier without any positive stop, and hence soundlessly.

Other objects of the invention, and the manner of attainment of these aims and those already indicated, are as set forth hereinafter.

An illustrative embodiment of the invention is shown in the accompanying drawings, in which

Fig. 1 is a side-elevation of the improved switch, Fig. 2 a plan view thereof, and Fig. 3 a side elevation from the opposite side from Fig. 1, with the casing or the mounting plate partly broken away.

Fig. 4 is an end-elevation of the same, with the casing partly broken away.

Fig. 5 is an end elevation showing one end of the switch, and Fig. 6 an end elevation of the other end.

Fig. 7 is a side elevation of the thumb piece and single pole contact maker carried thereby.

Fig. 8 is a similar view of a thumb piece and double pole contact maker.

Fig. 9 is an end elevation of the part shown in Fig. 7.

Fig. 10 is a detail showing the bearing for the thumb piece formed in the switch case.

Fig. 11 is a side elevation, Fig. 12 a plan view, and Fig. 13 an end elevation, of the mounting which supports the moving parts, with certain of the latter omitted.

Fig. 14 is a plan view of the switch case, showing the stationary contacts and the bulb illuminating the switch.

Referring to the drawings, the thumb lever comprises

2

a thumb piece 1, of Lucite or other translucent plastic, a pivot 3 received in notches 5 in the switch case 7 of molded plastic or other dielectric material, and an extension part 9, preferably metallic, connected by a pivot 5 pin 11 fixed therein to a shoe 13 slidably mounted on a guide rod 15 extending parallel to the plane of swing of the extension 9.

Hole 17 in shoe 13 is slightly larger than pivot 11 to permit the swing of the thumb piece 1 needed to work 10 the switch, but before shoe 13 reaches the bends in guide 15 the path of travel of pivot 11 away from the guide rod 15 in an upward arc centering on pivot 3 takes up the slack provided in hole 17 and in the passage occupied by 15 guide 15 and brings both the shoe 13 and the thumb 15 piece 1 to rest without shock or sound. The shoe is 20 preferably made of plastic of slightly yielding nature.

The usual actuating pull spring 19, Figs. 2 and 4, is 25 provided to accelerate the thumb piece and carry it and extension 9 through their full stroke initiated by the user's 30 fingers, and to hold the parts securely in either the on or off position. This spring is attached at one end to a stud 21 at the bottom of extension 9 of the thumb lever and at the other end to a pin 23 on a straight spring carrier or toggle lever 25, pivoted at 27 to a back plate 29 in 35 which the legs 31 of guide 15 are fixed as by riveting or welding. This back plate is mounted in the switch case 7 by sliding its flanges 33 down into L-shaped slots 35, Fig. 14, in one side wall of the switch case 7. Spring carrier 25 is pivotally attached at 37 to another shoe 39 40 having a hole whereby it is slidably mounted on a second guide rod 41 welded to back plate 29 and extending across the opening 43 therein. Lost motion permitting the needed swing of spring carrier 25 is provided by making this hole, or the hole in the shoe for pivot 37, or 45 both, slightly oversized, a clearance of .005" being adequate and insufficient to allow the parts to slap audibly. Since pin 37 through shoe 39 travels in an arc about pivot 27 of the spring carrier, and guide rod 41 extends in a straight line, the same jamming action occurs with 50 shoe 39 as with shoe 13 to bring the spring carrier to rest after the desired amount of angular movement of the spring carrier at each side of the vertical, by reason of the divergent paths defined by pivot 37 and rod 41 as 55 spring carrier 25 moves back and forth.

In use, manual movement of the thumb lever 1 to the left in Fig. 1 stretches the toggle spring 19 and carries the bottom end thereof past the line joining centers 23 and 27 as the spring carrier stands in inclined position at one end or the other of its swing. Then the spring 50 carrier snaps over in the direction of travel of the bottom end of extension 9 of the thumb lever, pulling the extension along with it to complete the stroke of the thumb lever to close the circuit. Identical but opposite movement of the parts occurs when thumb lever 1 is moved 55 in the opposite direction to open the circuit.

Closing of the circuit is effected by the entry of a contact maker 43 comprising a section of silver tubing fixed on the end of one of the arms 45 of extension 9, in between two arcuate silver plated metallic contact 60 members 47 fixed on rectangular metal plates 49 equipped with binding screws 50, and slipped into slots 51 formed in one end wall of switch case 7. The taper of the opposing faces of contacts 47 toward each other in the upward direction is so slight that contact 43 enters between them soundlessly. The checking of the moving parts is not caused by the entry of contact 43 thus, but as already explained is effected by the combined binding action of shoes 13 and 39 on their respective guides 70 15, 41.

Because spring carrier 25 moves very rapidly under the impulse of its spring 19 when it snaps over, spring

buffers 52 are mounted on guide rod 41 to act as shock absorbers to help stop the fast traveling shoe 39. These springs are long enough to engage the shoe just before the latter reaches its binding point on guide 41, so as to slow it down. The binding action of the shoe on rod 41 prevents material recoil of the shoe on encountering either spring 52. These springs help prevent reverse creep of extension 9 and its contact 43, by tending to erect spring carrier 25 and hence further stressing spring 19, thus holding extension 9 in place.

Guide rod 15 for thumb lever shoe 13 is bent into U-shape in plan (Fig. 12) so as to provide a slight and resilient endwise movement of the guide. Thus the stresses transmitted to the guide rod by the binding action of shoe 13 in arresting the movement of the thumb lever are cushioned and not transmitted to the back plate and switch case to cause noise; i. e., the shock is transverse to the legs 31 instead of lengthwise thereof.

For easy conversion to a three-way switch, so-called, the other arm 45 of thumb piece extension 9 is also equipped with a contact 44, Fig. 8, and slots 55, Fig. 14, are formed in one end of the switch case 7, into which may be slipped the base portions of a pair of contacts 59, similar to 47. Only one of these slots 55 extends clear through the wall of the case, to permit attachment of a wire to the binding screw 61 of one of the contacts 59, the other of such contacts lacking a binding screw and being connected at 63 to one of the contacts 47. When a three-way hook-up is not wanted, a plastic filler piece 57, Fig. 5, is inserted to close opening 55.

Continuous illumination of the switch to help locate it in the dark is provided by a neon tube 65, Fig. 14, either loose or if preferred fixed by clip 67 in the bottom of the switch case 7, and permanently connected by leads 69 in the circuit passing through contacts 47 and 59. Translucent thumb piece 1 thus glows with constant light from tube 65.

From the foregoing it will be plain that the arrest of the motion of the parts is caused by the mechanical opposition to further travel of the shoes caused by one surface guiding each of them in a straight path while another surface seeks to compel it to travel in a diverging arcuate path, this action being combined with the friction of each shoe against its guide rod incident to these conflicting motions. Obviously, the guide rods or other interfering or diverting surface need not be straight. The parts are brought to rest so nearly soundlessly that the operation of the switch is inaudible from a distance of approximately four feet when the switch is in place in a wall and covered by the usual wall plate. Wear makes no significant change in the action or quietness, because of the steep slope of the arcs.

It is to be noted that the construction provides for the complete assembly of all working parts outside of and before mounting in the switch case 7, save the lamp 65 and the contacts 47, 59. Thus the mounting of all but these latter parts on back plate 29 is the key to high-speed economical quantity production, because these parts can be assembled outside the switch case with complete accessibility and accuracy employing jigs and spot welding. Mounting of the back plate with the parts carried thereby as a unit is effected after assembly by merely sliding the flanges 33 of the back plate down into slots 35. The wiring of the contacts 47, 59, to each

other and to lamp 65 is likewise effected outside the case, the contacts being thereafter slipped into their proper slots and the lamp being positioned in the bottom of the case by the leads 69 attached to the contacts 47.

5 Mounting plate or cover 71 is thereafter applied and fixed in position by screws 73 put into lugs 75 formed on the ends of the case.

In the event that any of the moving parts of the switch become disabled or inoperative in use, replacement of 10 the back plate and the parts carried thereby as a unit is easily effected upon merely taking off the mounting plate 71. Thus the improved switch can easily and cheaply be restored to operative condition, instead of having to be discarded and entirely replaced with the attendant trouble of shutting off the current to the switch and disconnecting and then reconnecting the wires thereto.

While I have illustrated and described a certain form in which the invention may be embodied, I am aware that many modifications may be made therein by any 20 person skilled in the art, without departing from the scope of the invention as expressed in the claims. Therefore, I do not wish to be limited to the particular form shown, or to the details of construction thereof, but

What I do claim is:

25 1. An electric switch having in combination a thumb lever, a spring carrier moving in an arc, a spring connecting these parts, shoes pivotally connected respectively to the thumb lever and the spring carrier, and guides for each shoe divergently disposed to the arc of travel of the pivot of such shoe.

2. An electric switch having in combination a thumb lever, a spring carrier moving in an arc, a spring connecting the thumb lever and the spring carrier, a shoe pivotally connected to the latter, and a guide for the 30 shoe divergently disposed with respect to the path of swing of the pivot of the shoe.

3. An electric switch having in combination a thumb lever, a spring carrier moving in an arc, a spring connecting the thumb lever and the spring carrier, a shoe 40 pivotally connected to the latter, a guide for the shoe divergently disposed with respect to the path of swing of the pivot of the shoe, and springs alternately engaged by the shoe in its travel in alternate directions along the guide.

4. An electric switch having in combination a mounting plate, an assembly of parts mounted thereon including a thumb lever, a spring carrier, a spring, guides, and shoes pivotally connected to the thumb lever and the spring carrier and traveling along such guides, and 45 a case having slots in its walls receiving the mounting plate and the parts carried thereby as a unit.
